Primary Examiner — Ania Aman

(57) **CLAIM**

The ornamental design for a vent accessory for vehicle heating and air conditioning systems, as shown and described.

DESCRIPTION

FIG. 1 is a front perspective view of a vent accessory for vehicle heating and air conditioning systems showing the new design;

FIG. 2 is a top view of the vent accessory for vehicle heating and air conditioning systems of FIG. 1;

FIG. 3 is a front elevation view of the vent accessory for vehicle heating and air conditioning systems of FIG. 1;

FIG. 4 is a right side view of the vent accessory for vehicle heating and air conditioning systems of FIG. 1;

FIG. 5 is a left side view of the vent accessory for vehicle heating and air conditioning systems of FIG. 1;

FIG. 6 is a bottom view of the vent accessory for vehicle heating and air conditioning systems of FIG. 1; and,

FIG. 7 is rear elevation view of the vent accessory for vehicle heating and air conditioning systems of FIG. 1.

In the drawings, any broken lines depict unclaimed subject matter only and form no part of the claimed design.
